UNITED STATES PATENT OFFICE.

MICHAEL J. TRACY, OF ST. LOUIS, MISSOURI, ASSIGNOR TO PAULY JAIL BUILDING COMPANY, OF ST. LOUIS, MISSOURI, A CORPORATION OF MISSOURI.

JAIL-DOOR-OPERATING MECHANISM.

Application filed December 29, 1926. Serial No. 157,818.

My invention has relation to improvements in jail door operating mechanism and consists in the novel features of construction more fully set forth in the specification and 5 pointed out in the claims.

The invention is more particularly directed to mechanism for operating a door or doors disposed in a plane at right angles to the plane of movement of the control levers, 10 which levers are adapted to operate other mechanism of which the present invention forms no part. Thus, the principal object of the invention is to translate the direction of the original motion to a direction at 15 right angles thereto and to provide mechanism for accomplishing this object which will be comparatively simple, positive in its action, and which may be actuated with a minimum of effort. A further object is to 20 provide a transmission between the parts that are disposed at right angles to each other, that shall be compact and that may be entirely encased so as not to permit of tampering by the inmates of the jail or any- 25 one unauthorized. Further and other advantages will be better apparent from a detailed description of the invention in connection with the accompanying drawings, in which:

30 Figure 1 is a side elevation (with parts in section) of the top of the jail door and the mechanism for operating said door, the door being shown in closed position; Figure 2 is a view similar to Figure 1, the door, how- 35 ever, being shown open; Figure 3 is a horizontal, longitudinal section through the cas- 40 ing that houses the door operating mechanism, said section being taken on a plane indicated by the line 3—3 in Figure 1, the operating mechanism being shown in plan; Figure 4 is a side elevation of the levers and bars connected thereto for transmitting the motion to the door, the housing being shown in section; Figure 5 is a vertical cross sec- 45 tion taken on the line 5—5 of Figure 2; Figure 6 is a perspective view of the plate for connecting the travel bar to the link transmission; and Figure 7 is an enlarged 50 sectional detail through one of the links.

55 Referring to the drawings, (Figures 1 and 3), D represents a jail door movable in a plane at right angles to the plane of movement of the primary door operating mechanism comprising an indexing lever 1 con-

nected to an index bar 2, and an operating lever 3 connected to a main travel bar 4.

The door D is suspended by rollers 5, 5 adapted to travel on a track 6 secured to a partition plate 7 above partition 8 and an extension or toggle lever 9 is pivotally connected to a lug 10 projecting from the center of the top horizontal door bar 11, the upper end of extension lever 9 being pivotally connected to a bracket 12 secured to plate 7 (as shown in Figures 1 and 2). The door D is provided with a keeper 13 adapted to enter a slot 14 in the inner face of the hollow door jamb 15, said keeper being engaged by the upper edge of an opening 16 in a locking or drop bar 17, said bar 17 having an angle plate 18 secured to its upper extremity. A trip lever 19 is pivotally mounted on a pin 20 at about its center, said lever 19 carrying a roller 21 on its outer end. The roller 21 is operable in a slot 22 in plate 23 secured to the index bar 2. From the foregoing it will be apparent that if the index lever 1 and index bar 2 are moved to the appropriate position, the plate 23 carried by the index bar 2 will be moved so that the roller 21 will be forced into the lower part 22' of slot 22, thereby rocking the lever 19 and raising the drop bar 17 so as to release it from the door keeper 13 and unlocking the door D. The rocking of the lever will also raise the angle bracket 18 which in turn will lift the free end of a special jump bar 24 which traverses a slot 25 in said angle bracket. It will be observed that the jump bar 24 is pro- 65 vided with a lug 24' extending laterally 70 from its upper edge, said lug being adapted to enter a notch 26 in the bottom edge of a special travel bar 27, said bar being sup- 75 ported at its free end between rollers 28, 28' 80 (as shown in Figures 1 and 2). Thus when the door D is to be opened, the index lever 2 is moved to its proper position whereupon the door D is unlocked and at the same time 85 the jump bar 24 is coupled to the travel 90 bar 27.

100 The door is then indexed, or selected, and, if now the operating lever 3 is raised, the door will be opened by means of the right angle door operating mechanism which includes the special travel bar 27 and a link transmission T connecting the special travel bar to the main travel bar 4.

105 The link transmission T comprises a plu-

rality of links 31 connected by spindles 32 between links 33, 33, said spindles having rollers 34, 34 mounted on their outer ends. The rollers 34 are each provided with bosses, 35, 35 in which are depressions 36, 36 to receive the head 32' of spindle 32 and retaining washer 37 respectively, the latter being held in place by the upset extremity 38 of the spindle. The terminal links 33, 33 are connected respectively to plates 39, 40, which plates have laterally extending arms 39' and 40' perforated to receive spindles 32, 32. Plate 39 extends downwardly through a slot 41 in the bottom of casing 42 which houses and confines the transmission T and is riveted to the main travel bar 4. There are two openings 43, 43 in the plate 39 into which are inserted spindles 44, 44 carrying suitable rollers 45, 45 rotatable in a plane transverse to the rotation plane of rollers 34, 34. Plate 40 extends downwardly through a slot 41' in the bottom b of the casing 42 and is provided with spaced openings 46, 46 onto which are inserted spindles 47, 47 carrying rollers 48, 48 disposed in the same plane as rollers 45, 45.

Thus, the main travel bar 4 actuates the special travel bar 27 through the transmission T, and a movement of bar 27 is effective on the jump bar 24 when it has been raised to engage the notch 26 in said travel bar 27. As the travel bar 27 is moved to a position either to open or close the door D, it will oscillate the extension lever 9, the latter 35 swinging from one side to the other and carrying with it in its movement the door D. When the door D is opened, the movement of the jump bar 24 is multiplied by the extension lever 9 so that for a given movement of the bar 27, the door D will move twice the distance. It is readily seen that the advantage of this arrangement of lever is that the throw of the operating lever may be comparatively short. In order to 45 have the moving parts operate easily, they are provided with suitable roller bearings shown in the drawings, but not specifically described since the use of antifriction bearings is an old expedient and is not herein claimed.

In the operation of the invention, the lever 1 is moved to actuate the index bar 2, thus moving the plate 23 in the direction of the arrow (Figure 4) until the roller 21 has 55 been forced into the bottom 22' of the slot 22, rocking the lever 19 to the position shown in Figure 2, thereby raising the plate 18 to unlatch the door D and at the same 60 lift the jump bar 24. When the jump bar is raised, its lug 24' enters the notch 26 in the travel bar 27, thus coupling said travel bar and jump bar together. If the lever 3 is now actuated, the main travel bar 4 will be moved in the direction of the arrow 65 (Figure 4), and the transmission T will

also be moved through the casing 42, said transmission through its connection with the special travel bar 27 actuating said bar 27 in the direction of the arrow (Figure 1). Since the special travel bar 27 is now coupled to the jump bar 24, as above set forth, the jump bar 24 will be caused to travel from the position shown in Figure 1 to that shown in Figure 2 and the door will be opened owing to the connection between the jump bar 24 and lever 9. As the transmission is moved through the casing 42, the rollers 44 will roll along the sides of the casing 42 with a minimum of friction, and the rollers 45 will roll along the bottom b of said casing. The lower rollers 34 will slide along the bottom b, but the friction between the rollers and said bottom is reduced to a minimum by virtue of the depression b' extending longitudinally of the bottom b (Figure 7). By virtue of the rollers 34, 45, and the reduction of the contact between lower rollers 34 and the bottom b of the casing 42, the friction between the transmission and its casing is reduced to a minimum so that the door D may be opened with comparatively little effort.

While I show the transmission T in combination with a jail door operating mechanism, it is apparent that this transmission may be employed for other uses and I do not wish to be understood as restricting myself to the specific application herein described.

Having described my invention, I claim:

1. In a jail door operating mechanism, the combination of an operating lever, a travel bar connected thereto, a special travel bar disposed at right angles to the said travel bar, flexible means for translating the motion of the travel bar to the special travel bar, and means for coupling the door to the special travel bar.

2. In a jail door operating mechanism comprising a travel bar and an operating lever therefor, a special travel bar disposed at right angles to the travel bar, flexible means for imparting the motion of the main travel bar to the special travel bar, means for locking the door in closed position, and means for unlocking said door and simultaneously therewith coupling the door to the special travel bar.

3. In a jail door operating mechanism comprising a travel bar and an operating lever therefor, a special travel bar disposed at right angles to the travel bar, flexible means for imparting the motion of the main travel bar to the special travel bar, means for coupling the special travel bar to the door, and an indexing lever adapted to actuate the coupling means.

4. In a jail door operating mechanism, the combination of an operating lever, a travel bar connected thereto, a special travel bar

disposed at right angles to the said travel bar, a plurality of links connecting the travel bar and the special travel bar, whereby motion of the former is imparted to the latter, 5 and means for confining the links to their path of travel.

5. In a jail door operating mechanism, the combination of an operating lever, a travel bar connected thereto, a special travel bar 10 disposed at right angles to the said travel bar, a plurality of links connecting the travel bar and the special travel bar, whereby motion of the former is imparted to the latter, and a suitable housing for said links.

15. 6. In a jail door operating mechanism, the combination of an operating lever, a travel bar connected thereto, a special travel bar disposed at right angles to the said travel bar, a flexible connection composed of a series 20 of links between the travel bar and the special travel bar, said links having rollers at their pivotal points.

7. In a jail door operating mechanism, the combination of an operating lever, a travel bar connected thereto, a special travel bar 25 disposed at right angles to the said travel bar, a flexible connection composed of a series of links between the travel bar and the special travel bar, a housing for confining the links to their path of travel, and rollers 30 at the pivotal points of the links adapted to give said flexible connection rolling support in the housing.

8. In a jail door operating mechanism, the combination of an operating lever, a travel bar connected thereto, a special travel bar disposed at right angles to the said travel bar, a plurality of links connecting the travel bar and the special travel bar, whereby motion of the former is imparted to the latter, 35 and a suitable guideway for said links.

In testimony whereof I hereunto affix my signature.

MICHAEL J. TRACY.
